GUY LINE AND SHEAVE MEANS FOR USE IN CONNECTION WITH HOISTING AND HAULING MACHINES

Application filed July 23, 1929. Serial No. 380,334.

My invention relates to improvements in guy line and sheave means for use in connection with hoisting and hauling machines of the form commonly termed tower skidders and the object of my invention is to provide guy line and sheave means in combination with the folding main spar of a tower skidder, in which the guy lines extend longitudinally through said main spar and pass over sheaves in said main spar, which sheaves are mounted in planes substantially parallel to the plane in which said main spar moves when it is tilted for folding whereby tension may be maintained on any or all of said guy wires during the time said main spar is being lowered.

A further object is to provide a novel arrangement of sheaves within the main spar which will avoid cramping the guy lines when the main spar is lowered into a horizontal position.

Tower skidders of the form used in logging operations embody a relatively long heavy horizontal main frame adapted to be transported on railroad trucks and arranged to be supported above a railroad track in an elevated position so that empty flat cars may pass freely thereunder during log loading operations. This frame carries all of the apparatus in the nature of winding engines and the like which is necessary to the hauling in and loading of logs and further carries a main spar, usually from ninety to one hundred feet long, that serves as a support for one end of a sky line which is used as a track cable over which logs from the woods may be hauled in to the location of the tower skidder. This main spar is necessarily very heavy, and due to its great length, has a very great leverage on the skidder frame.

The lower end of this main spar is pivotally mounted in an upright tower on the skidder frame so that said main spar may be lowered or swung downwardly into a substantially horizontal position and the free end of the same rested on a separate flat car when the machine is to be moved. To support the upper end of this long main spar it is necessary to use several guy lines and

it is very desirable that these guy lines be arranged so that any desired amount of tension can be maintained on any or all of said lines during the raising and lowering of said main spar. I accomplish this object by mounting the lower guy line sheaves within and on said main spar in planes substantially parallel to the plane in which the main spar moves when it is being raised or lowered and by arranging said sheaves so that the guy lines will always draw fairly over the sheaves and there will be no cramping or binding of said guy lines.

Other and more specific objects will be apparent from the following description taken in connection with the accompanying drawings.

In the drawings, Figure 1 is a fragmentary view partly in section and partly in elevation of a tower skidder having an arrangement of guy lines and sheaves constructed in accordance with my invention, showing the main spar in a raised position, the middle portion of said main spar being broken away.

Fig. 2 is a fragmentary view partly in elevation and partly in section of the lower end of the main spar and parts of the tower, the main spar being in a lowered position.

Fig. 3 is a cross section of said main spar taken substantially on broken line 3-3 of Fig. 1.

Fig. 4 is a detail, being a plan view of the engine and winding drums for the guy lines.

Fig. 5 is a sectional view on a larger scale substantially on broken line 5-5 of Fig. 1.

Referring to the drawings, throughout which like reference numerals designate like parts, 10 is a horizontal main skidder frame, adapted to be supported on railroad trucks 11 for movement on a railroad track 12. When the skidder is in use the trucks 11 are removed and the skidder frame blocked up high enough above the track 12 so that empty cars may pass freely thereunder. One or more engines, not shown, are mounted on the skidder frame for driving hoisting and hauling drums 14. A turntable 15 carrying a boom 16 together with suitable drum and engine means 17 is mounted on the for-

ward end of the horizontal frame. An upright tower 18 is rigidly mounted on the frame 10 between the drums 14 and the turn-table 15 and a main spar 20 is pivotally mounted within said tower on vertically movable trunnion means 21, said trunnion means being more fully described in my co-pending application Serial No. 380,331 filed of even date herewith.

10 The main spar 20 is forked at its lower end affording a shorter arm 22 and a longer arm 23. The longer arm 23 serves as a lever which is connected by sheaves 24 and 25 and cable 26 with power operated drum 27 whereby said main spar may be raised and lowered.

15 In accordance with my invention, I provide within the bottom end of the main spar 20, at the location of the fork portions 22 and 23, six rollers 28, 29, 30, 31, 32 and 33 which are mounted for rotation in planes parallel to the plane in which the main spar swings when it is being raised or lowered. The rollers 28 to 33 inclusive serve as fair-25 leads and guide means for four guy lines 34, 35, 36 and 37 which are wound on drums 38, 39, 40 and 41.

20 The guy lines 34 to 37 extend upwardly through the main spar 20 to the top end thereof and pass outwardly over four sheaves 42 which are preferably mounted for rotation in planes arranged at an angle of forty-five degrees to the planes of the lower rollers 28 to 33 whereby the guy lines may

35 extend outwardly at an angle of approximately forty-five degrees to the fore and aft center line of the machine. From the sheaves 42 the guy lines 34, 35, 36 and 37 preferably extend outwardly and around sheaves 43 and thence back and are secured as at 44 to the top of the main spar. Other guy lines 45 are secured to the sheaves 43.

40 The drums 38, 39, 40 and 41 are driven through gears, 46, pinions 47, shaft 48, pinion 49, gearwheel 50, shaft 51, gearwheel 52, pinion 53, shaft 54 and crank disc connections 55 to motor 56. Clutches 57 are provided between the pinions 47 for selectively engaging any of said pinions and driving any drum independently of the other drums. Suitable brake means 58 are provided in connection with each drum and each of said drums is also provided with a ratchet 45 for locking the drum when the cable thereon is allowed to stand under tension.

45 In the operation of this invention the lower sheaves 28 to 33 inclusive, being mounted in planes parallel to the direction in which the main spar moves when it is being raised or lowered make it possible at all times to exert any desired amount of tension on any or all of the guy lines while the main spar is being raised or lowered. When the main spar is in any other position 60 between the vertical and horizontal the guy

lines will draw around the sheaves as shown in Fig. 2.

The foregoing description and accompanying drawings clearly disclose what I now regard as a preferred embodiment of my invention but it will be understood that this disclosure is merely illustrative and that changes in the device may be made within the scope of the following claims.

75 I claim:

1. The combination with the pivotally mounted main spar of a tower skidder, of guy lines extending lengthwise through said main spar and guide sheaves for said guy lines mounted for rotation in the lower end of said main spar in planes substantially parallel with the plane in which said main spar is moved when said main spar is turned into and out of operative position.

80 2. The combination with the pivotally mounted main spar of a tower skidder, of guy lines extending lengthwise through said main spar and passing outwardly over guide means at the top of the same, winding drum means upon which the lower ends of said guy lines are wound and a plurality of sheaves mounted for rotation in the lower end of said main spar in planes parallel with the plane in which said main spar is moved in raising and lowering the same, said 85 sheaves forming a fair-lead for said guy lines whereby tension may be maintained on any or all of said guy lines during a turning movement of said main spar.

90 3. The apparatus as claimed in claim 2 in which the guide means at the top of the main spar is in the nature of sheaves rotatably mounted in planes arranged at an angle of substantially forty-five degrees relative to the plane of movement of the main spar.

95 4. The combination with the pivotally mounted main spar of a tower skidder, of four guy lines extending lengthwise through said main spar and passing outwardly at the top of said main spar, independent winding drum means on the skidder for each of said guy lines and six sheaves mounted for rotation in the lower end of said main spar in planes substantially parallel to the plane in which said main spar is moved in raising and lowering the same, said sheaves forming fair-lead means for said guy lines whereby tension may be maintained on any or all said guy lines during a turning movement of said main spar.

100 In testimony whereof I hereunto affix my signature.

105 KNUTE BERGER.
